UNITED STATES PATENT OFFICE.

BENJAMIN LAWRENCE, OF LEYTON, ENGLAND,

ELECTRIC IGNITION-GENERATOR.

1,092,370.

Specification of Letters Patent.

Patented Apr. 7, 1914.

Application filed June 3, 1913. Serial No. 771,430.

To all whom it may concern:

Be it known that I, BENJAMIN LAWRENCE, a subject of the King of England, residing at Leyton, in the county of Essex, England, have invented certain new and useful Improvements in Electric Ignition-Generators, of which the following is a specification.

This invention relates to electric ignition generators which are provided with means for obtaining at certain times an acceleration of the armature, the said means being known as armature-tripping devices or starting-trips.

When it is desired to start an internal combustion engine from rest by turning the engine-shaft, a certain speed must usually be attained before the electric ignition generator or, as it is usually termed, the ignition-magneto, will generate a spark to fire the explosive mixture. This turning of the engine-shaft is, especially with large engines, very laborious, and it is therefore desirable that the speed of the ignition-magneto should be accelerated with relation to that of the engine-shaft in order that a spark may be generated while the engine-shaft is turning at a speed normally insufficient to produce such a spark. Numerous starting-trip devices have been proposed to attain this desideratum, especially by the insertion in the drive between the engine-shaft and the ignition-magneto, of a spring element which is compressed or placed under tension and then tripped to produce a faster speed of the armature than would be obtained by the direct drive.

It is an object of the present invention to produce an improved starting-trip which shall be comparatively cheap and simple to manufacture, shall be composed of a relatively few and strong parts and shall be reliable and simple in its operation. According to the present invention this object is attained by providing an ignition-magneto starting trip having in combination a driving-shaft, a driving-member so mounted thereon as to rotate therewith and also slide along the same, a spring to slide the said member in one direction, a trip consisting of a cam and cam roll (or its equivalent) to slide it in the opposite direction, a driven-member fixed to the armature-shaft and means operatively connecting the driving and driven members so that the driven-member always rotates when the driving-member rotates and also rotates but at a

greater speed than the driving-member, when the latter is moved endwise by its spring.

It is sometimes desirable, especially with heavy engines, that, if the crank-shaft has stopped in the correct position, the engine should be started without being turned by external means, and it is a further object of the present invention to produce an ignition-magneto starting-trip which is capable of producing a spark adequate to fire the explosive mixture when the engine is at rest, and according to the present invention such means will be provided by making one of the tripping elements movable by external means and independently of the engine-shaft to trip the armature.

These and other features of the invention will be described with reference to the accompanying drawings, and will be pointed out in the claims, but it is to be understood that the invention is not limited to the constructions shown in the drawings.

In the drawings, Figure 1 is a perspective view of the magneto showing the sleeve through which the armature-shaft is connected to the driving-member; Fig. 2 is a perspective view partly in section of the driving-member with its spindle and the parts mounted thereon. Fig. 3 is a perspective view of the casing which incloses the driving-member and which is bolted to a part of the framework of the magneto; Fig. 4 is a longitudinal section on the line 4-4 of Fig. 5; Fig. 5 is a cross-section on the line 5-5 of Fig. 4. Fig. 6 is a cross-section on the line 6-6 of Fig. 4. Fig. 7 is a side elevation partly in section of an ignition-magneto provided with a modified form of starting-trip; Fig. 8 is a perspective view of certain of the parts shown in Fig. 7, and Fig. 9 is a side elevation partly in section of a modified form of the device shown in Fig. 7.

The magneto-armature-shaft has fixed to it a sleeve A having formed in it two cam slots A¹, which as shown in Fig. 1, are each provided with a part A² which lies parallel with the axis of rotation of the shaft. A spindle B is suitably connected to the engine shaft and carries at one end an enlargement formed as a cup B¹ to fit over the sleeve A. Surrounding the cup is a sliding driving-member which takes the form of a sleeve C which carries internally two feathers C¹ adapted to slide in guide-ways

- B² cut in the cup B¹. Fixed in each feather is a pin C² carrying a cam-roll C³ adapted to operate in the cam slots A¹. The sliding sleeve is pressed toward the armature 5 by a spiral spring C⁴ which surrounds the sleeve and is located between a rib B³ on the cup B¹ and a corresponding rib C⁵ upon the sliding sleeve, the forward movement of the sleeve being limited by a collar B⁴ on the end of the cup nearest to the armature. 10 On its outer surface the sleeve C is provided with two cams D each having an operative face D¹, which cams form one element of the trip.
- 15 When the sleeve is moved endwise against the action of its spring and then released, there would be a hammering between the end of the sleeve and the collar B⁴ that limits its forward movement, and this hammering would ultimately result in damage to the parts. To avoid such hammering a buffer is inserted between the end of the sleeve and the collar, which buffer takes the form of a floating collar B⁵ surrounding the cup. 20 This floating collar is pressed away from the collar B⁴ by small spiral springs B⁶ located in pockets B⁷ in the side of the collar adjacent to the sleeve, the movement of the floating collar under action of these springs B⁶ being limited by pegs fixed in the outer surface of the cup. 25 In order that these pegs may not contact with the sleeve C the latter is recessed at C⁶.
- 30 A casing E incloses the mechanism just described and is provided at one end with a flange E¹ which is bolted to a corresponding flange on the frame of the machine, and has at the other end an aperture through which the spindle B passes. If desired the spindle instead of bearing directly upon the casing may be supported in ball-bearings which are in turn supported in a recess in the casing. 35
- The casing E is provided with two orifices 40 over which are fixed two cylindrical chambers F in each of which is located a plunger F¹ adapted to be pressed through its orifice into the path of the driving-member cam D by a spring located between the end of the chamber F and the adjacent end of the plunger F¹. To limit the motion of the plunger and to prevent it from rotating it has passing through it a stud F² whose ends project at each side and slide in grooves F³ 45 cut in the walls of the chamber F. One end of the stud F² projects completely outside the chamber and carries a roller F⁴ for a purpose to be mentioned.
- 50 When the engine is turned, as for example by cranking, the spindle B is rotated and consequently the cup B¹ and the sliding sleeve or driving-member C are also rotated. During such rotation the operative faces D¹ of the driving-member cams D will strike 55 the ends of the plungers F¹ and since these

are stationary the sleeve C will be forced back against the action of its spring C⁴. This causes the cam-roll C³ to move back along the cam slots A¹ so that when the plungers reach the highest point of the cams D the cam-rolls will be at the outer end of the cam slots A¹. When the highest point of the cams pass the plungers F¹ the sliding sleeve C is moved back rapidly under the action of its spring and the cam-rolls C³ by 70 reason of the shape of the cam slots A¹ accelerate the speed of the armature sufficiently to cause a spark which will fire the explosive mixture in the ordinary manner. It may be mentioned that normally the cam-rolls C³ lie in the straight parts A² of the cam slots A¹ and thus provide a direct drive between the engine and the armature. Obviously, this accelerating action upon the armature is not required when the engine is 80 turning sufficiently fast to produce a spark without such acceleration, and accordingly, in order that the wear upon the parts may be reduced to a minimum, means are provided for causing cessation of the tripping action by removing one of the tripping members from the path of the other. 85

The outside of the casing is provided with a groove in which is mounted an oscillating setting ring G on which are formed two surface cams G¹ adapted to lie underneath and operate upon the rollers F⁴ which, as already mentioned, are mounted upon the plungers F¹. These cams G¹ are so shaped that in 90 one position of the setting ring (see Fig. 6) the plungers F¹ are withdrawn (by action of the cams G¹ on the rollers F⁴) from the path of the driving-member cams D and in another position (see Fig. 5) of the setting ring the cams G¹ permit the plungers to be 95 moved by their springs into the path of the driving-member cams. The first position may be called the operative position of the setting ring and the second its inoperative position. 100

The setting ring carries an arm G² which is connected by a spring G³ with some stationary part in such a manner that the setting ring is normally held in operative position so that the plungers are normally out of 115 action. The arm G² is also connected by a cord or the like to a hand-operated lever so that the driver can at will remove the setting ring to the other end of its travel in order to permit the plungers to move under the action of their springs into the path of the driving-member cams D. 120

In order that it may not be necessary for the driver to continue to hold the setting ring in such inoperative position a locking device is provided which acts automatically to lock the setting ring as soon as it reaches the said position. The upper portion of the casing E carries a small rock-shaft H which at one end is provided with a detent H¹ 130

adapted to engage with a notch G^4 in the outer surface of the said ring when the latter is moved to inoperative position. The rock shaft has a spiral spring H^2 surrounding it and tending always to rock it in such a direction as to cause engagement of the detent H^1 with the notch G^4 . Thus when the setting ring has been set by the driver it will continue to be held in that position until released.

As the acceleration of the armature is only required until the engine has attained a certain speed, it is convenient to so design the apparatus that the lock upon the setting ring shall be automatically released when the engine has attained a speed sufficient of itself to cause proper sparking of the magneto. Accordingly the other end of the rock shaft H is provided with a lever H^3 which when the detent H^1 is in locking position, projects approximately radially through the casing E into close proximity with the surface of the collar B^4 . This collar B^4 is provided with two recesses B^9 in each of which is located a striker B^{10} . When one of the strikers is in the neighborhood of the lever H^3 and is stationary, it will fall into the bottom of the recess B^9 under the action of gravity. When however, it is rotated centrifugal action will tend to throw it outward until at a certain speed it will project so far beyond the surface of the collar B^4 that its point will strike the lever H^3 and will rock the rock shaft H to remove the detent H^1 from the notch G^4 . Immediately this occurs the spring G^2 will oscillate the setting ring G to remove the plungers F^1 from the path of the cams D . In order that the lever H^3 may be clear of strikers B^{10} whenever the setting ring has been retracted into its normal position, another surface cam G^5 is provided upon the setting ring and is so placed that when the detent H^1 is removed from the notch G^4 the first movement of the setting ring G will cause the edge of the detent to contact with the lowest point of this cam. As the setting ring moves around to its normal position, the detent will pass over the surface of the rising cam and will gradually be moved in a direction to rock the lever H^3 so that the latter is moved into a recess E^2 in the casing and thus is out of range of the strikers B^{10} . In order that the strikers B^{10} and the lever H^3 may not be damaged should the mechanism be for any reason rotated backwardly, their rear surfaces are rounded. Consequently upon such rotation the strikers would on striking the lever H^3 merely be removed down into their recesses.

Instead of providing the plungers F^1 with cam-rolls to coöperate with the cams D they are provided with flats F^6 to coöperate with the acting surfaces D^1 which flats are located parallel with the said surfaces. The plun-

gers have also further flats F^6 to coöperate with the highest parts of the cams D , these flats being provided to prevent the rounding of the surfaces on either the plungers or the cams by reason of a sharp edge upon one or the other. The ends D^4 of the cams D are slightly undercut in order that when tripped they may be free of the plungers F^1 and thus cause no wear by reason of contact with the said plungers during the rapid forward movement of the sleeve C under action of its spring. These ends D^4 of the cams together with the corresponding surfaces F^7 of the plungers F^1 are beveled in such a manner that the plungers will readily ride over the cams should the mechanism for any reason be revolved backwardly, and thus the liability of the parts to damage is greatly decreased.

A modified form of starting-trip comprising a single mechanism which, at will, operates the said trip either from the engine-shaft or from a hand-lever independently of any motion of the engine-shaft, will now be described. As in the previous construction, the magneto-armature shaft has fixed to it a sleeve J provided with cam slots J^1 each of which has a part J^2 parallel with the axis of rotation of the shaft. A spindle K is suitably connected to the engine-shaft and carries at one end a feather K^1 which fits a groove in a sleeve K^2 . Thus the sleeve is forced to rotate with the spindle but can slide longitudinally thereon. The sleeve K^2 is provided with a flange K^3 serving as an abutment for a spring K^4 whose other end rests against the inner face of a cover K^5 pinned at K^6 to the spindle K . Projecting internally from the sleeve K^2 are pins K^7 (or rollers) adapted to coöperate with the cam slots J^1 . Mounted upon an extension of the magneto-frame and surrounding the sleeve J , is an oscillating setting-ring L which is normally held at one end of its movement by a spring. The setting-ring is grooved at L^1 to receive a cord L^2 or the like by means of which it may be partially rotated. Upon a cylindrical extension L^3 of the setting-ring are cut two cam peaks which are reached by faces L^4 , L^5 and are located opposite each other. It will be noticed that the cam faces at L^6 are of "slow" pitch and have therefore, very little cam action. Upon the rear face L^5 of each cam peak, a small depression provides a shoulder L^7 for a purpose to be explained. In order to limit the oscillating motion of the setting-ring L it has formed upon it two shoulders L^8 facing opposite ways, which are adapted to coöperate with a stop L^9 projecting from the frame of the machine. The arrangement is such that the setting-ring L can be rotated through an angle of 180° or thereabout. A floating cam-ring M is provided of such an internal diameter as to take a bearing upon the cylindrical

extension L^2 . Secured to the interior of the cam-ring M are cam-blocks M^1 , each of which is provided with a face M^2 of such a width as to fill the depression between the shoulder L^7 and the base L^6 of the cam face D^4 . In this way, the face M^2 constitutes a lock for the cam-ring M under certain circumstances. The cam-ring M is provided near its end remote from the magneto with an internal flange M^4 having two clutch-dogs M^5 which are so placed as to engage with other clutch-dogs K^8 when the tripping mechanism is in operation; the clutch-dogs K^8 are formed in the face of the flange K^3 . The floating cam-ring M has a V-shaped flange M^6 upon its exterior which coöperates with the bent ends of spring blades (one of which is shown dotted in Fig. 7 at L^{10}) projecting from the magneto-frame. In this way, the floating-ring is normally retained in its inoperative position close to the setting-ring L ; when the parts are in this inoperative position, the dogs K^8 and M^5 are not in engagement with each other. A stop M^7 is adapted to contact with one of the spring blades L^{10} and so limit the rotation of the cam-ring M . If the engine has stopped in such a position that there is a compressed charge in one of its cylinders and the crank has moved over the dead-center, the engine may be started from rest without cranking. To do this the driver operates a hand-lever or the like connected with the cord L^2 and causes the setting-ring to move against the action of its spring. If the stop M^7 is not in contact with the spring blade L^{10} the floating cam-ring M will be carried around by the cam-face L^4 until such contact is made and will then be held from further rotation. Thereafter, the cam-faces L^4 , as they move around, will cause the cam-blocks M^1 to ride up the faces L^4 of the setting-ring, and so bring the flange M^4 into contact with the flange K^3 . Further rotation of the setting-ring L carries around the ring M until the dogs M^5 and K^8 engage and lock the sleeve K^2 and cam-ring M together. Continued rotation of the setting-ring L causes the cam-blocks M^1 to ride up the peaks of the setting-ring to force back the sleeve K^2 to compress the spring K^4 . Upon further rotation of the setting-ring L the cam-blocks ride over the peak of the cam and the spring K^4 forces the sleeve K^2 rapidly back to its original position, and this movement rotates the armature sufficiently quickly to give an adequate spark. When it is desired to use this starting-trip by cranking or otherwise rotating the engine-shaft, it can be done in the following manner: The setting-ring L is first rotated sufficiently by the cord L^2 to cause engagement of the clutch-dogs K^8 and M^5 . Then the engine-shaft is turned to rotate the spindle K and therefore, the arma-

ture-shaft. This rotation causes the cam-blocks M^1 to ride up the stationary cam-faces L^4 as in the previous method of operation, and tripping will be performed as before. It will be seen that the setting-ring L must be re-set after each tripping operation to bring the clutch-dogs K^8 and M^5 into engagement again. Repeated operations by cranking without re-setting of the setting-ring L may be effected by the employment of a distance-piece such as the pivoted finger L^{11} to keep the dogs clutched. Means such as the cam L^{12} (Fig. 9) may be provided to withdraw the distance-piece when no further repetitive action is desired. It will be appreciated that it is convenient to provide a definite point at which the tripping movements take place and for this reason the shoulders L^8 and stop L^9 are provided to limit the oscillating movement of the setting-ring L . The amount of movement allowed for the ring is such that if it has to travel a considerable distance before the clutch-dogs K^8 and M^5 are brought into engagement, sufficient further movement will not be available to enable the cam-blocks M^1 to pass the cam peaks and effect tripping. Such an occurrence would indicate that the crank shaft was not in the proper position for the explosive mixture to be fired.

The provision of the sloping (instead of merely straight) rear cam-faces L^5 and M^2 enables the period or angle within which the armature may be tripped to be increased so that effective firing of the explosive mixture may take place even if the crank-shaft is not in the best position, that is to say, if it has not just passed the dead-center.

If the rear cam-faces L^5 and M^2 were smooth inclines the setting-ring in returning to its normal position would have a tendency to cause longitudinal movement of the sleeve K^2 ; the shoulder L^7 and faces M^3 are provided to prevent such a possibility.

In Fig. 9 is shown a modified form of mechanism for preventing repetitive action at high speeds. This mechanism is constituted by pivoted pawls O , the tails of which are forced inwardly by small leaf-springs. When the engine reaches a speed which is of itself sufficient to cause adequate sparking the pawls O under centrifugal action turn about their pivots and their noses O^1 fall behind shoulders O^2 formed near the periphery of the sliding sleeve K^2 as soon as the latter is moved forward to compress the trip-spring. As a result, the sleeve will be held outward so that the clutch-dogs K^8 and M^5 will fail to engage again and repetitive tripping action will be prevented until the speed of the engine becomes sufficiently slow to allow the noses of the pawls to move upward under action of their springs. Fig. 9

also illustrates a device for obtaining greater power for the starting trip. A torsion spring P has one of its ends secured to the cover K⁶ while the other end is secured to the sliding sleeve K². The latter, instead of being feathered as formerly, is provided with a spiral feather P¹ which engages with a corresponding spiral groove P² in the cover. Thus, as the sliding sleeve K² is forced backward by the tripping mechanism, it will also be rotated against the action of the spring P. Consequently, when the tripping occurs, the sleeve will be forced toward the armature not only by the usual spring K⁴, but by 15 the torsion spring P and in a spiral direction. In Fig. 9 there is also shown a convenient but well-known method of timing the parts which is constituted by a face-coupling R of the adjustable pin-and-slot type.

20 What I claim as my invention and desire to secure by Letters Patent is:—

1. An ignition-magneto starting-trip having in combination a driving-shaft, a driving-member so mounted thereon as to rotate therewith and also slide along the same, a spring to slide the said member in one direction, a trip consisting of a cam and cam-roll to slide it in the opposite direction, a 25 driven-member fixed to the armature-shaft, and means operatively connecting the driving and driven members so that the driven-member always rotates when the driving-member rotates and also rotates but at a greater speed than the driving-member when the latter is moved endwise by its spring.

2. An ignition-magneto starting-trip having in combination a driving-shaft, a driving-member so mounted thereon as to rotate therewith and also slide along the same, a spring to slide the said member in one direction, a trip to slide it in the opposite direction the said trip having one of its members fixed to the said driving-member, a 40 driven-member fixed to the armature-shaft, and means operatively connecting the driving and driven members so that the driven-member always rotates when the driving-member rotates, and also rotates but at a greater speed than the driving member when the latter is moved endwise by its spring.

3. An ignition-magneto starting-trip having in combination a driving-shaft, a driving-member so mounted thereon as to rotate therewith and also slide along the same, a spring to slide the said member in one direction, a cam rigidly secured to the said driving-member, an element to contact with the operative face of the said cam and slide 55 the driving-member in the other direction, means for withdrawing the said element from the path of the said cam, a driven-member fixed to the armature-shaft, and means operatively connecting the driving and driven-members so that the driven-

member always rotates when the driving-member rotates and also rotates but at a greater speed than the driving-member when the latter is moved endwise by its spring.

4. An ignition-magneto starting-trip having in combination a driving-shaft, a driving-member so mounted thereon as to rotate therewith and also slide along the same, a spring to slide the said member in one direction, a cam rigidly secured to the said driving-member, a plunger to contact with the operative face of the said cam and slide the driving-member in the other direction, a spring and a cam, the one to move the said plunger into the path of the driving-member cam and the other to remove it from the said path, a driven-member fixed to the armature-shaft, and means operatively connecting the driving- and driven-members so that the driven-member always rotates when the driving-member rotates and also rotates but at a greater speed than the driving-member when the latter is moved endwise by its spring.

5. An ignition-magneto starting-trip having in combination a driving-shaft, a driving-member so mounted thereon as to rotate therewith and also slide along the same, a spring to slide the said member in one direction, a cam rigidly secured to the said driving-member, a plunger to contact with the operative face of the said cam and slide the driving-member in the other direction, a spring tending to press the plunger into the path of the driving-member cam, an oscillating cam normally actuated by a spring to withdraw the plunger from the said path, means to move the oscillating cam into its inoperative position to permit the plunger to be pressed into operative position, a lock 90 operating automatically to lock the oscillating cam in its inoperative position, means operating automatically at or about a predetermined speed to release the said lock, a driven-member fixed to the armature-shaft, 95 and means operatively connecting the driving- and driven-members so that the driven-member always rotates when the driving-member rotates, and also rotates but at a greater speed than the driving-member, 100 when the latter is moved endwise by its spring.

6. An ignition-magneto starting-trip having in combination a driving-shaft, a driving-member so mounted thereon as to rotate therewith and also slide along the same, a spring to slide the said member in one direction, a cam rigidly secured to the said driving-member, a casing inclosing the starting-trip, a plunger mounted on the casing and passing through an orifice therein into the path of the driving-member cam, a spring tending to press the plunger into the said path, an oscillating setting ring mounted in a groove in the casing and carrying a cam to 115

co-act with the plunger, a spring normally acting to move the setting ring to operative position to cause its cam to withdraw the plunger from the path of the driving-member cam, means under the control of the driver to move the setting-ring to inoperative position, a detent carried by a rock-shaft, a spring acting on the rock-shaft to cause the detent to engage a notch in the setting ring when the latter has been moved to inoperative position, a lever mounted on the rock-shaft and projecting through the casting into the proximity of a rotating part, a striker located in a recess in the said rotating part and adapted at a certain speed, to fly out and strike the lever and rock it to release the detent from the notch, a driven-member fixed to the armature-shaft, and means operatively connecting the driving and driven members so that the driven-member always rotates when the driving-member rotates, and also rotates but at a greater speed, than the driving-member, when the latter is moved endwise by its spring.

25 7. An ignition-magneto starting-trip hav-

ing in combination a driving-shaft, a sleeve mounted to rotate therewith and also to slide along the same, a spring to slide the sleeve in one direction, a cam rigidly secured to the said sleeve and forming one element of the trip, another element to contact with the operative face of the cam and slide the sleeve in the other direction, means for withdrawing the said other element from the path of the sleeve-cam, a driven-member fixed to the armature-shaft, a cam-roll mounted upon the sleeve internally and operating in a cam-slot in the said driven-member so that the driven-member always rotates when the sleeve rotates, and also rotates, but at a greater speed than the sleeve, when the latter is moved endwise by its spring.

In testimony whereof I have signed my name to this specification in the presence of two subscribing witnesses.
